SUCTION CLEANER NOZZLE

Eugene F. Martinec, East Cleveland, Ohio, assignor to Health-Mor, Inc., Chicago, Ill., a corporation of Illinois

Application March 21, 1955, Serial No. 35,135

Term of patent 14 years

(Cl. D9—2)

Fig. 1

Fig. 3

Fig. 1 is a perspective view of a suction cleaner nozzle showing my new design;

Fig. 2 is a side elevational view thereof; and

Fig. 3 is a front elevational view thereof.

I claim:

The ornamental design for a suction cleaner nozzle, substantially as shown.
